ABSTRACT OF THE DISCLOSURE

This disclosure relates to a furnace construction with easily removable roof sections. A billet heating furnace has a longitudinal heating chamber through which billets are passed from an entrance to an exit end. Billets are heated by direct flame impingement on the billets. Hot gases are withdrawn through the top of refractory sections which form the sides and top of the heating chamber. A casing which is spaced from the refractory section encloses the furnace. The hot gases from the heating chamber are withdrawn through exhaust conduits extending down from the top of the external casings above each refractory section. Bottom portions of the exhaust conduits are removable to permit each furnace section to be lifted and moved above adjacent furnace sections. Mov-
able hoist means are provided within the casing for lifting the furnace sections and moving the lifted sections above the adjacent sections so that rapid access can be obtained to the heating chamber interior. Means are pro-
vided on the refractory sections for engaging the hoist members so that the sections can be easily raised.

This invention relates to billet heating furnaces having an external casing with built-in means for lifting the furnace sections for rapid access to the interior of the furnace.

In the extrusion of longitudinal members from metals such as aluminum, for example, heated billets are pressed through a die considerably smaller than the billets. The billets are heated in order to facilitate the extrusion.

A furnace has recently been developed to heat billets rapidly and seriatim. The furnace has a longitudinal chamber which is relatively small in cross-section. The billets are conveyed or pushed through the longitudinal chamber from an entrance end to an exit end. The billets are rapidly heated by direct impingement of flames from a plurality of burner tiles spaced along the longitudinal chamber between the entrance and exit ends. The hot gases generated within the furnace must be removed by an exhaust system in order to maintain effective heating of the billets. A spaced external casing is provided with exhaust conduits extending from the interior of the longitudinal chamber through the refractory walls and through the external casing to a point exteriorly of the building in which the furnace is located. The spaced external casing is highly desirable to prevent oil fires from hydraulic fluid and to minimize the danger of burns to employees.

Due to operators' errors and for various other reasons, a billet can become blocked within the chamber and/or a melt down can occur. When this happens, the furnace must be shut down and direct access must be obtained to the section of the furnace which contains the blocked billet or the melt down in order to clear out the problem. Other problems of repair to the interior of the furnace can occur and direct access must also be obtained to that portion of the furnace. Since the furnace chamber is relatively small in cross-section, access to the interior through the entrance or exit is not feasible. The external casing and the exhaust system preclude the use of an

2

overhead crane for removal of the various furnace sections.

It has been proposed to make the furnace in sections and to use a fork lift truck, for example, to remove different upper sections of the furnace after portions of the exterior casing have been removed. The fork lift truck, however, causes damage to the refractory portions of the furnace. Further, there is usually not enough space in the plant to permit a fork lift truck to move alongside the furnace so as to remove the damaged sections.

The invention of this application seeks to overcome these prior art problems by making the furnace with removable upper sections, providing hoist means between the furnace and the exterior casing, and providing an effective exhaust system which can be adapted to permit removal of the furnace sections for repairs and recon-
struction.

By various aspects of this invention one or more of the following, or other, objects can be obtained.

20 It is an object of this invention to provide a longi-
tudinal billet heating furnace having means to provide quick access to the interior portions thereof.

25 It is a further object of this invention to provide a billet heating furnace in which billets are heated by direct flame impingement, the furnace having an adequate ventilation system wherein rapid access to the interior of the furnace is provided without damaging furnace compo-
nents.

30 It is yet another object of this invention to provide an improved billet heating furnace with easily removable furnace sections which are transportable along the furnace and easily replaceable with a minimum of down time.

35 Other aspects, objects, and the several advantages of this invention are apparent to one skilled in the art from a study of this disclosure, the drawings, and the appended claims.

40 According to the invention there is provided a billet heating furnace having a longitudinal heating chamber formed from a plurality of upper refractory sections and lower refractory sections. The longitudinal heating chamber has an entrance end and an exit end. Heating means are spaced along the side of the furnace for heating the billets within the heating chamber by direct impingement of the flame on the billets. Means are provided for pass-
ing the billets through the heating chamber from the entrance end to the exit end. A casing surrounds the furnace and includes a top and side walls. Gas removal means are provided for withdrawing the removing gases within the furnace through the top of the upper refractory sections and through the casing top.

45 Means are provided within the casing to raise individual upper refractory sections so that direct access can be had to the furnace interior. Preferably, the raising means comprises a track means within the casing ex-
tending longitudinally of the furnace and hoist means movably supported by the track so as to be longitudinally movable above the furnace. A cable is provided on the hoist having an end raisable and lowerable by the hoist.

50 Means on the upper refractory sections are provided for engaging the end of the cable so that the upper refractory sections can be raised by raising the end of the cable.

55 The gas removable means are constructed so as to permit raising the furnace sections and moving each longi-
tudinally of the furnace above the top of the other furnace sections.

60 The invention will now be described with reference to the accompanying drawings, in which:

65 FIG. 1 is a perspective view of a furnace construction embodying the invention with the side wall partly broken away;

FIG. 2 is a side elevational view in section of the furnace shown in FIG. 1; and

FIG. 3 is a cross-sectional view taken along lines III—III of FIG. 2.

Referring now to the drawings, the furnace is enveloped by an outer casing 12 with an exhaust collector duct 13 forming a roof. The outer casing 12 has removable side wall panels 12a which are retained by downwardly extending flanges 15 at the top upwardly extending flanges 17 at the bottom of the panels. The furnace comprises an upper furnace section 14, a burner section 16 and a lower furnace section 18. The furnace is supported by cross beams 20, longitudinal beams 22 and risers 24.

The furnace forms a longitudinal heating chamber 16 for heating the billets 32 shown in phantom lines in the drawings.

The billets are supported within the longitudinal heating chamber 26 on rollers 30 rotatably supported by channel members 28. The billets are heated by flames which are projected from burner tiles 36. Fuel lines 34 supply fuel to the burner tiles 36. The flames from the burner tiles impinge directly on the billets and envelop the billets.

The lower furnace section 18 is encased by a metal bottom casing 38 having outwardly extending flanges 40 at the top portion thereof. Holes are provided in the casing 38 for the passage of the fuel lines 34.

The upper furnace section 14 has a refractory portion 42 with an exhaust aperture 44. A metal casing 46 is fixed to the outer portion of the refractory 42 by embedded connecting rods 48. The metal casing 46 has an outwardly extending flange 50 adjacent flange 40 of the bottom casing. The metal casing 46 has brace members 52 which are coextensive with the sides of the casing as seen in FIG. 3. Brace bars 64 are fixed to adjacent brace members 52 in a given furnace section. Support rods 66 having anchors 68 embedded in the refractory are positioned beneath the brace bars 64 and extend outwardly at the sides of the upper furnace sections 14. Each support rod 66 has a downwardly turned handle.

The furnace is made from a plurality of furnace sections comprising refractory portions 42 and metal casings 46. Each refractory portion has beveled corners 54, leaving a small open area around the edge of each section. This open area is filled with a loose refractory filler material 56 and is covered by a cover plate 58. The cover plate has an outwardly directed flange 60 to which bolts 62 are attached and through which bolts 62 the cover plate is secured to the flange 40 of the metal bottom casing 38. The cover plate overlaps the edges of the metal casing 46. Each brace member 52 is spaced a sufficient distance from the edge of the furnace section 14 to permit the cover plate 58 to slide laterally on a section 14 so that adjacent sections can be lifted and removed without interference from the cover plate 58.

Upright support members 70 having cross beam members 72 support I-beam rails 74 which extend longitudinally within the furnace. Overhead trolley hoists 76 ride on the rails and are adapted to raise individual upper furnace sections 14 within the external casing. The trolley hoists 76 comprise wheels 78 rotatably secured to depending arms 80. An eyelet 82 is fixed at the bottom of arms 80 for a hook 84. A hoist 86 is fixed to the hook 84 and carries a cable 88 with a loop 90 for engaging the support rods 66.

Exhaust conduits 92 are positioned above the exhaust apertures 44 for removing the hot gases from the interior of the furnace. Each exhaust conduit communicates with the exhaust collector duct 13. A fan 94 is provided to withdraw the hot gases from the exhaust collector duct 13.

Each exhaust conduit 92 has an extension 93 fixed at the bottom thereof through a machine screw 98. A damper valve 100 is positioned within the extension 93 and has a handle 102 for adjusting the position of the valve 100 to regulate the flow of gases through the ex-

haust conduit 92. The extension 93 is adjustable so that the distance from the bottom of the extension 93 to the top of the refractory section 14 can be adjusted. The bottom of extension 93 is spaced from the top of the refractory section to permit ambient air to be drawn into the conduit to cool the same. By this system, the gases being withdrawn from the furnace are cooled to 400-500° F., thereby eliminating the need for insulated ducts. The bottom of the extension is spaced close enough to the top of the refractory section 14 to provide enough draft to keep the gasses moving through the furnace and while keeping the exhaust conduit at a desired temperature.

The upper portion of exhaust conduit 92 has outwardly directed flanges 104 at the exhaust collector duct 13. The exhaust conduit 92 is supported through flanges 104 by angle bar supports 106 which are fixed on the bottom of the exhaust collector duct 13. In this manner, the exhaust conduit 94 can be easily removed in order to permit lifting of the refractory section 14.

In this kind of furnace wherein the billets are heated by direct flame impingement, a high flow of gases is required. The hot gases must be continually withdrawn through the top of the furnace through conduits 92. The external casing minimizes the danger of fire due to oil which may be exposed to the hot burners. The external casing further prevents dissipation of heat into the area surrounding the furnace during normal operation of the furnace.

In operation, when it is desirable to obtain access to the interior portions of the furnace, the side walls 12a of the casing 12 are removed. The exhaust conduit 92 above the section to be removed is forced toward the front or back of the furnace to disengage flanges 104 from the angle bar supports 106. The exhaust conduit 92 can then be lowered and removed. In a similar manner, the exhaust conduit adjacent the section to be removed is also removed. The hoists 76 are positioned overhead of the upper section to be removed. Bolts 62 of cover plate 58 on either side of the section to be removed are loosened so that the cover plates can be moved to adjacent sections. The cover plates 58 are then moved laterally to free the upper furnace section to be moved. The loops 90 of cable 88 are then positioned over the lift bars 66 in a manner which has been illustrated in FIG. 1. The hoists are activated to raise the furnace section to a position illustrated by phantom lines in FIG. 3. The furnace section, being wholly supported by the trolley, can be wheeled along the length of the furnace by the trolleys to open the furnace for repairs. If desirable, all lower portions of conduits 92 can be removed and the furnace section 14 can be wheeled down to the end of the track for removal from the hoist by lift truck or similar article. A new furnace section can then be positioned on the hoist and lowered in place to replace the removed furnace section. The open areas between the furnace sections are then filled with filler material and the cover plates 58 are replaced and bolted in place.

The built-in hoist permits rapid access to the interior of the furnace chamber in case of product melt down or to clear any product jams that may occur. The access is obtained without the use of forklift trucks which can damage the refractory sections and cause premature replacement of the furnace sections.

Further, the built-in hoist means provides a simple method of removing sections of the furnace where space requirements preclude the use of machinery such as forklift trucks to remove the furnace sections.

Reasonable variations and modifications are possible within the scope of the foregoing disclosure, drawings and appended claims without departing from the spirit of the invention.

The embodiments of an invention in which an exclu-

sive property or privilege is claimed are defined as follows:

1. In a billet heating furnace having:
a longitudinal heating chamber formed from refractory material including a plurality of upper refractory sections;
an entrance end and an exit end in said heating chamber;
heating means spaced along the sides of said heating chamber for heating billets within said heating chamber by direct flame impingement of said billets; means for passing billets through said heating chamber from said entrance to said exit end;
a casing surrounding said furnace including a top wall and side walls;
gas removal means for withdrawing and removing gases within said furnace through the top of said upper refractory section and through said casing top wall;
the improvement which comprises:
track means within said casing above said upper refractory section extending longitudinally of said furnace;
hoist means movably supported by said track means so as to be longitudinally movable above said furnace;
a cable on said hoist having an end raisable and lowerable by said hoist; and
means on said upper refractory section for engaging said end of said cable, whereby raising 30 of said cable by said hoist can lift a furnace section engaged by said cable end to permit access to the interior of said furnace.
2. A billet heating furnace according to claim 1 wherein in said gas removal means comprises at least one exhaust aperture in an upper portion of said upper refractory section, said aperture extending through said upper refractory section; exhaust conduits depending from said casing top wall above and spaced from said aperture, at least a bottom portion of said exhaust conduit being removable so as to permit said sections to be raisable and movable longitudinally of said furnace over and above other of said sections.
3. A billet heating furnace according to claim 1 wherein in each upper refractory section has a top and depending 45 sides; said engaging means comprise bars extending out of opposite of said sides of said refractory sections.
4. A billet heating furnace according to claim 3 wherein in each refractory section has a metal casing on the outer portion thereof, said metal casing being fixed to said refractory sections by anchor means embedded in the refractory sections and secured to said metal casing.
5. A billet heating furnace according to claim 4 wherein in said metal casings have brace members extending upwardly along the sides and laterally of the top thereof,

5

10

15

20

25

30

35

perpendicular to the surface of said casings, and brace bars extending horizontally between adjacent brace members on said sides of said metal casing on each refractory section, said brace members being positioned above and contacting said bars extending out of the sides of said refractory sections so as to reinforce said bars in said refractory sections.

6. A billet heating furnace according to claim 1 wherein in said track means comprises two tracks extending longitudinally above and on either side of said heating chamber, and hoist means are movably supported on each track so that said upper refractory sections can be supported on each side as the same is raised.

7. In a billet heating furnace having:
a longitudinal heating chamber formed from refractory material including a plurality of upper refractory sections;
an entrance end and an exit end in said heating chamber;
heating means at the sides of said furnace for heating billets within said heating chamber as said billets pass through said heating chamber;
means for passing said billets through said heating chamber from said entrance end to said exit end;
a casing, spaced from said refractory material, surrounding said furnace and including a top wall and side walls;
gas removal means for withdrawing and removing gases from within said furnace and through said upper refractory sections and through said casing;

the improvement which comprises:
hoist means within said casing and above said longitudinal heating chamber adapted to engage each refractory section and raise said section to a position wherein direct access can be obtained to the interior of said longitudinal heating chamber.

8. A billet heating furnace according to claim 7 wherein in at least a portion of said side walls of said casing are removable for direct access to the interior of said longitudinal heating chamber.
